BEAN-SHOOTING PISTOL

Hearl D. Jones, 114 N. 29th St., and Paul E. Snider,
2616 Alameda Road, both of Louisville, Ky.
Filed Oct. 17, 1960, Ser. No. 63,161
3 Claims. (Cl. 124—27)

This invention relates to toys, and more particularly to toy pistols.

The principal object of the present invention is to provide a rapid-fire repeating target pistol which will fire as ammunition in addition to target beans, spherical devices of wood, plastic, or rubber.

The body of the pistol and most of its component parts can be advantageously manufactured of hard plastic, or other similar material, as hard rubber.

Another object of the invention is to provide a target pistol embodying a minimum number of working parts. It will, consequently, lend itself to the most inexpensive cost in production. The simplicity of design ensures its durability in target use. In design, and this feature is unique, the bean itself does the actual shooting; the trigger can be pulled at will, and, unless a bean is in shooting position, the spring will never move or be activated in the least. This pistol cannot be "snapped" without actually shooting.

In the accompanying drawings, several embodiments of the invention are shown:

FIGURE 1 is a vertical sectional elevation.

FIGURE 2 is a vertical sectional elevation showing the pistol in firing position.

FIGURE 3 is a rear elevation showing the bean container and the method of permitting the beans to go around the barrel.

FIGURE 4 is an elevation of the loading bar assembly.

FIGURE 5 is a plan view of the loading bar.

FIGURE 6 is a vertical sectional elevation showing the central portion of the pistol.

FIGURE 7 is a sectional plan showing the baffle wings and the slotted loading bar housing.

FIGURE 8 is a rear elevation of the loading bar proper, showing the position of the firing spring and the pin which retains the loading bar in the pistol.

Referring to the drawings wherein like numerals indicate like parts, it can be seen that, in operation, the bean 9 enters the bean container 10 through hole 13, falling around barrel 11 across baffle wings 12 and into loading position at the bottom of bean container 10. The bean 9 is selected by loading bar 18, falling into the bean carriage hole 22 in loading bar 18 through slot 15 in loading bar housing 14.

It is advantageous at this time to point out that once the loading bar 18 moves to the rear toward cocking position, that the bean carriage hole 22 moves through the loading bar housing 14 leaving only the solid section of loading bar 18 contiguous to the bottom of bean container 10. Therefore, only one bean can leave the bean container in each firing cycle.

Please note, too, at this time, that the loading bar 18 is angularly disposed in a vertical plane with respect to the barrel 11 (horizontal and above), the barrel 11 intersecting the loading bar housing 14 at the rear end of the barrel 11.

As the loading bar moves rearward and upward, the bean 9 engages the firing spring 24 (pressure is exerted on the bean 9 by the forward edge of the carriage hole 22, said pressure being transmitted through the bean 9 to firing spring 24) bending the spring 24 in tension until

2

said carriage hole registers with the hole through said barrel. At that instant, said bean is projected through the barrel, the firing spring being free to straighten, the spring moving through slot 16 and hole 17 in loading bar housing, said slot and hole in registration with slot 21 and hole 22 in said loading bar.

After firing, the trigger 19 with its monolithic loading bar 18 is returned to loading position by coil spring 26.

Referring to FIGURE 6 and FIGURE 7 (Sheet 2 of drawings), it will be noted that the baffle wings 12 are designed to serve a dual purpose, i.e., they prevent jamming of the firing mechanism by the total weight of a full container of beans; they also enable the pistol (when the bean container is only partially filled), to fire in all reasonable firing positions, i.e., sidewise, straight up or straight down.

In FIGURE 2 it will be noted that handle 28 is recessed to accommodate the movement of the trigger guide 20 through the trigger guide housing 25. It will be noted, too, in FIGURE 2 that the firing spring 24 is rigidly anchored on its lower extremity in handle 28.

It will be advantageous, now, in referring to FIGURE 8, that the pin 23 retains the loading bar 18 in pistol, it being placed after the loading bar has slid past the spring. The pin also permits adjustment of the loading bar for proper registration when in firing position.

While the foregoing description sets forth the invention in specific terms, it is to be understood that numerous changes in shape, size and materials may be resorted to without departing from the spirit and scope of the invention as claimed hereinafter.

Having thus described our invention, we claim as new and desire to secure by Letters Patent:

1. In a repeating toy bean-shooting pistol, a movable loading bar angularly disposed in relation to the pistol barrel; said loading bar provided with an expanded slot for the introduction of a bean from a bean container above; said loading bar moving upward and to the rear in firing, the plane of the loading bar intersecting the plane of the barrel; said loading bar engaging a firing spring in its motion to the rear and firing said bean as said expanded slot registers with the hole through said barrel.

2. In a repeating toy bean-shooting pistol, a funnel-shaped bean container enveloping a rear section of the pistol barrel; said container provided with baffle wings, one on either side of the barrel; said container connecting said barrel with a loading bar housing below which slopes upward toward the rear end of the barrel; the bottom of said container conforming to the angular disposition of the loading bar housing.

3. In a repeating toy bean-shooting pistol, the combination as described in claim 1, said loading bar made monolithic with a trigger, said trigger provided with a tubular trigger guide, said trigger guide fitted with slots for the movement of said trigger, and provided also with adequate anchorage in the pistol handle for stability of said trigger, and its alignment in the plane of the loading bar.
